P. BROWN.
OPERATING MECHANISM FOR BRAKES,
APPLICATION FILED DEC. 24, 1914.

Patented June 6, 1916.

2 SHEETS—SHEET 2

UNITED STATES PATENT OFFICE.

PERRY BROWN, OF CORAOPOLIS, PENNSYLVANIA.

OPERATING MECHANISM FOR BRAKES.

1,185,975.

Specification of Letters Patent. Patented June 6, 1916.

Application filed December 24, 1914. Serial No. 878,905.

To all whom it may concern:

Be it known that I, PERRY BROWN, a citizen of the United States, and a resident of Coraopolis, in the county of Allegheny and State of Pennsylvania, have invented certain new and useful Improvements in Operating Mechanism for Brakes, of which the following is a specification.

- This invention relates to brakes intended particularly for use on railway cars and more particularly to hand operated brakes adapted to be secured to the ends of freight cars, although it will be obvious that the brake is capable of use on other cars.
- 15 The object of the invention is to construct a brake which is exceedingly simple in construction, unlikely to get out of order and which can be easily operated by a brakeman with the use of one hand.
- 20 The invention consists in the combination and arrangement of parts shown, in their preferable embodiment, in the drawings accompanying and forming part hereof.

In the aforesaid drawings: Figure 1 is an end elevation of part of the end of a freight car with my invention applied thereto. Fig. 2 is a vertical central section of the same. Fig. 3 is a view with the back plate removed. Fig. 4 is a perspective view 30 of several of the parts detached. Fig. 5 is a detail showing a modified form. Fig. 6 is a sectional view of a modified form of drum.

Referring now to the details of the drawings by numerals: 1 designates a frame preferably of malleable casting which is adapted to be secured to the end or any convenient portion of a car and is provided with a horizontally projecting bracket 2 having 40 a downwardly projecting casing 3 and an arm 4 projecting from the end of the bracket substantially parallel with said casing. The rear side of the casing is intended to be closed by a cover 6 and a bolt 8 passes 45 through an opening in the downwardly projecting arm 4 and through the casing 3 and also through an opening in the cover 6 into the end plate of a car, and thereby secures the frame of my brake to the car. An additional bolt or securing means 10 may be employed at the upper end as illustrated in Figs. 1 and 2. The downwardly projecting arm 4 is provided with a lug 12 adapted to co-act with one of the flat sides 55 of the head of the bolt 8 and thus prevent said bolt from turning. The inner side of

the downwardly projecting arm 4 is provided with a large annular recess 14, and the casing 3 is provided with an opening 15 of the same diameter as the recess 14 in 6. This makes it possible to insert a drum 16 through the casing, before the cover has been applied, the drum having one head or flange 17 finding a bearing in the recess 14 and another head or flange 65 18 finding a bearing in the opening 15. The aforesaid bolt 8 passes through this drum 16 from one end to the other thereof. The drum is formed with a lug 20 preferably cast integrally with the head 17 of the drum 16, 70 to which a chain may be secured as indicated in Fig. 2, this chain being adapted to pass under the car and be secured to the brake beam in the usual manner. That part of the drum 16 which is located within 75 the casing 3 is provided with a rectangular or other brake shaft projection 22, on the end of which is cast an annular member 23. The rectangular member 22 is designed to fit into a similar opening in a ratchet wheel 80 24 so that the ratchet wheel is compelled to rotate with the brake drum 16 whenever said drum is rotated. The annular portion 23 is intended to form a trunnion to fit into a link or crank 25 so that the link or crank 85 25 may be moved upon said trunnion 23 as a pivot. The trunnion 23 projects just sufficiently from the end of the head 18 of the drum 16 to contact with the inside of the cover 6 so that when said cover 90 95 is placed in position and the bolt 8 inserted in place, there is just sufficient space left between the squared portion 22 and the cover 6 to permit the easy swinging of the link or crank 25 upon its trunnion 23. 95 The link or crank 25 has formed, preferably integrally therewith, a stud 26 upon which is pivotally secured the operating lever or handle 27, this handle 27 having its upper end projecting into the casing 3 100 and having an opening 28 therein within which fits the aforesaid stud 26. That part of the handle within the casing is also provided with a pawl 29 which is so located that when the lever or handle 27 is swung on the 105 stud 26, the pawl 29 will engage the teeth of the ratchet wheel 24 and said wheel may be rotated with its drum 16 by an upward pull imparted to the lever or handle 27. The casing is provided with an opening in 110 its rim as indicated at 30 in Fig. 3, and the upper end of the lever or handle 27 is pro-

vided with a curved arm 31 which is formed of the same curvature as the inside of the casing 3 so that said arm 31 will close the opening as the handle is moved to its lower position, as illustrated in Fig. 3. Instead of having a ratchet wheel 24, as illustrated in Fig. 3, I may use a friction disk 33, as illustrated in the modified form, Fig. 5, in which case the pointed end 34 of the operating lever or handle will engage the disk and grip it frictionally to cause said disk to move therewith when an upward movement is imparted to the lever or handle. And the drum and its disk or ratchet wheel 15 may be made integrally as shown in Fig. 6.

The upper side of the casing is also provided with an opening 38, and through this opening projects the handle 39 of a pawl 40, this pawl being pivoted upon a pivot 41 cast integrally with the inside of the cover 6. The construction of this handle and its pawl is such that the weight of the handle will normally hold the pawl 40 in engagement with the teeth of the ratchet wheel 24, and 25 will yet permit the ratchet wheel to be rotated, the pawl 40 slipping over each tooth as the ratchet wheel rotates.

In addition to the bolts 8 and 10 which have been described as securing the brake casing to the end of the car, I may also employ a third bolt 42, the head of which is counter-sunk in the casing 3, the inside of the casing being provided with a strengthening lug 43 through which the bolt 42 passes. The cover 6, in addition to having the pivot 41 cast integrally therewith, also has a lug 44 cast integrally, which projects into the casing and acts as a stop to prevent the link of crank 25 from moving too far 40 when the lever or handle 27 is released.

I desire to call attention to the extreme simplicity of my brake and to the ease with which it may be cast and assembled. The brake, including the casing 3, and the arm 4 is one casting, and in assembling the head 17 of the drum 16 is slipped through the opening 15 of the casing 3 until it is seated in its bearing in the recess 14 of the arm 4. Then the ratchet wheel 24 is slipped over 50 the square end of the drum 16. The ratchet wheel does not have to be screwed or riveted. The link or crank 25 may now have its stud 26 inserted in the opening 28 of the handle 27 and these two parts may be slipped into 55 position by placing the link or crank 25 so that it will fit over the trunnion 23 on the end of the drum 16. After this is done the handle 39 may be placed on the cover 6 so that the pivot 41 will project into the opening in the handle 39 and the cover and the handle 39 are placed in position so that the securing bolt 8 will pass through the casing 3, the arm 4, drum 16 and the cover 6, when 60 the entire brake is now ready to be secured to the end of the car.

In operation, the brakeman needs to use only one hand in lifting the brake handle or lever 27. As this lever is lifted, the first movement is to swing the pawl 29 into engagement with the ratchet wheel 24 and the continued upward movement of the lever or handle 27 will cause said ratchet wheel to rotate, thereby rotating the drum 16 and winding the brake chain. During the rotation of the ratchet wheel 24, the pawl 40 slips over 70 the ratchet wheel tooth by tooth and holds the same from counter-rotation. As soon as the brakeman moves the brake handle or lever to the upper end of its stroke, he allows the same to fall to the position shown in Fig. 8, when the operation may be repeated until the brake is applied to the extent required. When this is done, the brakeman merely releases the lever or handle 27 and it falls to the position shown in Fig. 3. When it is desired to release the brake, all that the 85 brakeman has to do is to move the lever 39 upwardly so that the pawl 40 will release the ratchet and the brake will be released.

From the foregoing it will be seen that I have invented a brake of exceedingly simple construction and while some of my claims specify that the casing is adapted to be secured flat against the end of a car, I do not limit my claims to such construction as it is obvious that the brake may be used in other places. Changes and modifications may therefore be made in the invention and references should be made to the claims to determine the scope thereof.

What I claim as my invention is:

1. In a device of the character described, a casing adapted to be secured flat against the end of a car, a drum projecting from said casing, and an operating lever or handle mounted in the casing and projecting through the edge of the casing and arranged to drop by gravity to a substantially vertical position to release said drum and to co-act with said drum to rotate the same when the handle is moved upwardly.

2. In a device of the character described, a casing adapted to be secured flat against the end of a car, a drum projecting from said casing, a ratchet wheel in said casing movable with said drum, and an operating lever or handle mounted in the casing and projecting through the edge of the casing and arranged to drop by gravity to a substantially vertical position to release said ratchet wheel and drum and to co-act with said ratchet wheel to rotate the same and said drum when the handle is moved upwardly.

3. In a device of the character described, a casing adapted to be secured flat against the end of a car, a drum projecting from said casing, a ratchet wheel in said casing movable with said drum, an operating lever or handle mounted in the casing and projecting

- through the edge of the casing and arranged to drop by gravity to a substantially vertical position to release said ratchet wheel and drum and to co-act with said ratchet wheel 5 to rotate the same and said drum as the handle is moved upwardly, and a pawl entering said casing and co-acting with said ratchet wheel to prevent counter-rotation thereof.
10. 4. In a device of the character described, a casing adapted to be secured to the end of a car, an arm projecting therefrom, a drum journaled in said casing and arm, and an operating lever or handle entering said 15 casing and arranged to drop by gravity to a substantially vertical position to release said drum and to co-act with said drum to rotate the same as the handle is moved upwardly.
5. In a device of the character described, 20 a casing adapted to be secured to the end of a car, an arm projecting therefrom, a drum journaled in said casing and arm, a ratchet wheel in said casing movable with said drum, and an operating lever or handle 25 entering said casing and arranged to drop by gravity to a substantially vertical position to release said ratchet wheel and to co-act with said ratchet wheel to rotate it and the drum as the handle is moved upwardly.
6. In a device of the character described, 30 a casing adapted to be secured to the end of a car, an arm projecting therefrom, a drum journaled in said casing and arm, a ratchet wheel in said casing and movable 35 with said drum, an operating lever or handle entering said casing and arranged to drop by gravity to a substantially vertical position to release said ratchet wheel and to co-act with said ratchet wheel to rotate 40 it and the drum as the handle is moved upwardly, and a pawl entering said casing and co-acting with said ratchet wheel to prevent counter-rotation of the same.
7. In a device of the character described, 45 a casing adapted to be secured to a car and an arm cast integrally therewith, a drum projecting through said casing and having bearings in said casing and arm, and an operating lever or handle entering said casing 50 and arranged to drop by gravity to a substantially vertical position to release said drum and to co-act with said drum to rotate it as the handle is moved upwardly.
8. In a device of the character described, 55 a casing adapted to be secured to a car and an arm cast integrally therewith, a drum projecting through said casing and having bearings in said casing and arm, a ratchet wheel in said casing movable with said drum, and an operating lever or handle arranged to drop by gravity to a substantially vertical position to release said ratchet wheel and drum and to co-act with said ratchet wheel to rotate it and said drum as the handle is moved upwardly.
9. In a device of the character described, 60 a casing adapted to be secured to a car and an arm cast integrally therewith, a drum projecting through said casing and having bearings in said casing and arm, a ratchet wheel in said casing movable with said drum, an operating lever or handle arranged to drop by gravity to a substantially vertical position to release said ratchet wheel and drum and to co-act with said ratchet wheel to prevent counter-rotation thereof. 70
10. In a device of the character described, 75 a casing adapted to be secured flat against the end of a car, a drum projecting from said casing, a ratchet wheel in said casing movable with said drum, and an operating lever or handle pivotally supported in position and having a pawl entering said casing and co-acting with said ratchet wheel, said handle being arranged to drop by gravity to a substantially vertical position to release said ratchet wheel and drum and to co-act with said drum as the handle is moved upwardly. 80
11. In a device of the character described, 85 a casing adapted to be secured to the end of a car, an arm projecting therefrom, a drum journaled in said casing and arm, a ratchet wheel in said casing movable with said drum, and an operating lever or handle pivotally supported in position and having a pawl entering said casing and co-acting with said ratchet wheel, said handle being arranged to drop by gravity to a substantially vertical position to release said ratchet wheel and to co-act with said ratchet wheel to rotate it and the drum as the handle is moved upwardly. 90
12. In a device of the character described, 95 a casing adapted to be secured to a car and an arm cast integrally therewith, a drum projecting through said casing and having bearings in said casing and arm, a ratchet wheel in said casing movable with said drum, and an operating lever or handle pivotally supported in position and having a pawl entering said casing and co-acting with said ratchet wheel, said handle being arranged to drop by gravity to a substantially vertical position to release said ratchet wheel and drum and to co-act with said ratchet wheel to rotate it and the drum as the handle is moved upwardly. 100
13. In a device of the character described, 110 a casing, a drum projecting from said casing, a link or crank journaled within the casing, and an operating lever or handle secured to said link or crank and arranged to drop by gravity to a substantially vertical position to release said drum and to co-act with said drum to rotate it as the handle is moved upwardly. 115
14. In a device of the character described, 120 a casing, a drum projecting from said casing, a link or crank journaled within the casing, and an operating lever or handle secured to said link or crank and arranged to drop by gravity to a substantially vertical position to release said drum and to co-act with said drum to rotate it as the handle is moved upwardly. 125
15. In a device of the character described, 130 a casing, a drum projecting from said casing, a link or crank journaled within the casing, and an operating lever or handle secured to said link or crank and arranged to drop by gravity to a substantially vertical position to release said drum and to co-act with said drum to rotate it as the handle is moved upwardly.

14. In a device of the character described, a casing adapted to be secured to the end of a car, an arm projecting therefrom, a drum journaled in said casing and arm, a link or 5 crank journaled within the casing, and an operating lever or handle secured to said lever or crank and arranged to drop by gravity to a substantially vertical position to release said drum and to co-act with said 10 drum to rotate it as the handle is moved upwardly.

15. In a device of the character described, a casing adapted to be secured to the end of a car, an arm projecting from said casing, a 15 drum journaled in said casing and arm, a ratchet wheel in said casing and movable with said drum, a link or crank journaled within the casing and movable with respect to said drum and ratchet wheel, and an 20 operating lever pivotally supported by said link or crank and having a pawl co-acting with said ratchet wheel, said operating lever or handle being arranged to drop by gravity to a substantially vertical position to release 25 said ratchet wheel and drum and to co-act with said ratchet wheel and rotate the same and the drum as the handle is moved upwardly.

16. In a device of the character described, 30 a casing adapted to be secured to the end of a car, an arm projecting from said casing, a drum journaled in said casing and arm, a ratchet wheel in said casing and movable with said drum, a link or crank journaled 35 within the casing and movable with respect to said drum and ratchet wheel, an operating lever pivotally supported by said link or crank and having a pawl co-acting with said ratchet wheel, said operating lever or 40 handle being arranged to drop by gravity to a substantially vertical position to release said ratchet wheel and drum and to co-act with said ratchet wheel and rotate the same and the drum as the handle is moved upwardly, and a pawl entering 45 said casing and co-acting with said ratchet wheel to prevent counter-rotation thereof.

17. In a device of the character described, 50 a framework comprising a casing adapted to be secured to the end of a car, said casing having an aperture therein forming a bearing, an arm cast integrally with said casing and having a bearing formed therein in line with the bearing in said casing, a drum journaled in the bearings in said casing and arm, a ratchet wheel within the casing movable with said drum, and an operating lever or handle having a pawl entering the casing, 55 said operating lever or handle being arranged to have its pawl co-act with said ratchet wheel and to drop by gravity to a substantially vertical position to release the pawl from the ratchet wheel.

18. In a device of the character described, 60 a framework comprising a casing adapted

to be secured to the end of a car, said casing having an aperture therein forming a bearing, an arm cast integrally with said casing and having a bearing formed therein in line with the bearing in said casing, a drum journaled in the bearings in said casing and arm, a ratchet wheel within the casing movable with said drum, a link or crank journaled within said casing, and an operating lever or handle secured to said link or crank and having a pawl arranged to co-act with said ratchet wheel, said lever or handle being arranged to drop by gravity to a substantially vertical position to release said ratchet wheel and to move 75 said ratchet wheel and drum as the handle is moved upwardly.

19. In a device of the character described, a framework comprising a casing adapted to be secured to the end of a car, said casing 80 having an aperture therein forming a bearing, an arm cast integrally with said casing and having a bearing formed therein in line with the bearing in said casing, a drum journaled in the bearings in said casing and arm, a ratchet wheel within the casing movable with said drum, a link or crank journaled within said casing, an operating lever or handle secured to said link or crank and having a pawl arranged to co-act with said 85 ratchet wheel, said lever or handle being arranged to drop by gravity to a substantially vertical position to release said ratchet wheel and to move said ratchet wheel and drum as the handle is moved upwardly, and a pawl entering 90 said casing and co-acting with said ratchet wheel to prevent counter-rotation thereof.

20. In a device of the character described, 95 a framework comprising a casing adapted to be secured to the end of a car, said casing having an aperture therein forming a bearing, an arm cast integrally with said casing and having a bearing formed therein in line with the bearing in said casing, a drum having 100 beads or flanges fitting the bearings in said casing and arm, a ratchet wheel in said casing movable with said drum, and an operating lever or handle having a pawl 105 entering said drum and co-acting with said ratchet wheel, said operating lever or handle being arranged to drop by gravity to a substantially vertical position to release the pawl from the ratchet wheel and to move 110 the ratchet wheel and drum as the handle is moved upwardly.

21. In a device of the character described, 115 a framework comprising a casing adapted to be secured to the end of a car, said casing having an aperture therein forming a bearing, an arm cast integrally with said casing and having a bearing formed therein in line with the bearing in said casing, a drum having 120 beads or flanges fitting the 125

bearings in said casing and arm, a ratchet wheel in said casing movable with said drum, a link or crank journaled within the casing, and an operating lever or handle 5 pivotally carried by said link or crank and having a pawl co-acting with said ratchet wheel, said operating lever or handle being arranged to drop by gravity to a substantially vertical position to release the pawl 10 from the ratchet wheel and to move said ratchet wheel and drum as the handle is moved upwardly on said link.

22. In a device of the character described, a framework comprising a casing and an 15 arm, a chain shaft journaled in said casing and arm, a ratchet wheel movable with said chain shaft, an operating lever or handle having a pawl entering said casing and co-acting with said ratchet wheel, and a 20 bolt passing through the aforesaid casing, arm and chain shaft.

23. In a device of the character described, a casing adapted to be secured to the end of a car, a chain shaft journaled therein and 25 having a flat sided end projecting within the casing, a ratchet wheel having an opening to fit said flat sided end of the chain shaft whereby the chain shaft and ratchet wheel must turn together, and an operating 30 lever or handle entering said casing and arranged to drop by gravity to a substantially vertical position to release said ratchet wheel and to move said ratchet wheel and rotate the chain shaft as the handle is moved upwardly. 35

24. In a device of the character described, a casing adapted to be secured to the end of a car, a chain shaft journaled therein and 40

having a flat sided end projecting within the casing, a ratchet wheel having an opening to fit said flat sided end of the chain shaft whereby the chain shaft and ratchet wheel must turn together, a link or crank journaled within the casing, and an operating lever or handle pivotally supported by 45 said link or crank and having a pawl co-acting with said ratchet wheel, said operating lever or handle being arranged to drop by gravity to release said ratchet wheel and to move the ratchet wheel and chain shaft as 50 the handle is moved upwardly.

25. In a device of the character described, a casing adapted to be secured to the end of a car, a chain shaft journaled therein and having a flat sided end projecting within 55 the casing, a ratchet wheel having an opening to fit said flat sided end of the chain shaft whereby the chain shaft and ratchet wheel must turn together, a link or crank journaled within the casing, an operating lever or handle pivotally supported by 60 said link or crank and having a pawl co-acting with said ratchet wheel, said operating lever or handle being arranged to drop by gravity to release said ratchet wheel 65 and to move the ratchet wheel and chain shaft as the handle is moved upwardly, and a pawl entering said casing and co-acting with said ratchet wheel to prevent 70 counter-rotation thereof.

In testimony whereof I affix my signature in presence of two witnesses.

PERRY BROWN.
